UNITED STATES PATENT OFFICE.

ANTON N. BIRKLAND, OF STREETER, NORTH DAKOTA.

ECCENTRIC.

1,250,271.

Specification of Letters Patent.

Patented Dec. 18, 1917.

Application filed January 11, 1917. Serial No. 141,856.

To all whom it may concern:

Be it known that I, ANTON N. BIRKLAND, a subject of the King of Norway, residing at Streeter, in the county of Stutsman and State of North Dakota, have invented certain new and useful Improvements in Eccentrics, of which the following is a specification.

This invention relates to an eccentric for mowing machines, binders and headers and the primary object of the invention is to provide an improved means for imparting a reciprocatory motion to the pitman attached to the cutting blades whereby the noise and thumping of the other crank wheels generally employed in devices of this character will be obviated.

A further object of the invention is to provide an eccentric for driving the pitman attached to a cutter bar of a grain cutting machine which will be steady and noiseless in its operation and constructed so that the pitman and eccentric may be easily detached when the occasion arises.

25 A further object of this invention is the provision of an eccentric which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a side elevation.

Fig. 2 is a top edge view.

40 Fig. 3 is a section on the line 3—3 of Fig. 1.

Referring to the drawing, wherein is illustrated the preferred form of my invention, and in which like numerals of reference indicate corresponding parts throughout the several views, the extension arm or pusher 1 may be attached to a mowing machine, binder, or header in any preferred manner. The eccentric casing comprises two semi-circular portions 2 and 3 in which the eccentric is arranged. The portion 2 of the casing has a tongue 4 which is secured to the end of the bar 1 by the cleats 5 and 6 which are bolted to the tongue 4 and the bar 1. 55 The lower half 2 and the upper half 3 of the casing for the eccentric are held in position

by a clamp band 7 which comprises two arcuate members 8 and 9 having their terminals fastened to the lower half 2 of the casing. The proximate ends of the arcuate members are provided with ears or lugs 10 through which a fastening bolt 11 is extended for clamping the arcuate members 8 and 9 together thereby retaining the upper portion or cap 3 of the casing in operative position. Within the casing the annular wall thereof is provided with two annular grooves 12 for providing a ball rest for the ball-bearings 13. The eccentric 14, as shown by Fig. 70 3 of the drawing, is of the same thickness as the width of the casing 3 and the periphery of the eccentric is also provided with grooves for forming ball races 15 in radial alinement with the ball races 12 and 75 for receiving the ball-bearings 13. An opening in the eccentric 14 is disposed at one side of the center thereof and receives the drive shaft 16 which is keyed to the eccentric as shown by Fig. 1 of the drawing. 80

The free rotation of the eccentric, by virtue of the ball-bearings 15, will be obvious and the cap 3 may be easily removed for the purpose of removing the eccentric when the occasion arises. A grease cup 17 is 85 mounted upon the casing for the purpose of supplying oil and grease to the ball-bearings within the same.

From the foregoing it will be observed that a very simple and durable eccentric has 90 been provided, the details of which embody the preferred form. I desire it to be understood however, that slight changes in the minor details of construction may be made without departing from the spirit of the invention or the scope of the claims hereunto appended. 95

I claim:

1. An eccentric attachment of the character described comprising a shaft, an eccentric mounted upon the shaft and comprising a circular disk having an opening at one side of the center thereof, for receiving the said shaft, the latter being keyed in the said opening to impart a rotary motion to the disk when the shaft is rotated, the periphery of the said disk having annular grooves laterally spaced apart to provide annular ball races, a casing comprising upper and lower sections adapted to be assembled to embrace the said eccentric and disposed in spaced relation to the periphery thereof, the 100 105 110

- said casing having inner annular ball races alined with the ball races in the said disk, a plurality of ball bearings mounted in the ball races and contacting with the disk and the said casing, a clamp band secured to the said casing and including two co-acting curved portions terminating above the center of the said casing and means for bolting the said portions together.
- 10 2. An eccentric attachment of the character described comprising a shaft and eccentric mounted upon the shaft and comprising a circular disk having an opening at one side of the center thereof, for receiving the said shaft, the latter being keyed in the said opening to impart a rotary motion to the disk when the shaft is rotated, the periphery of the said disk having annular grooves laterally spaced apart to provide annular ball races, a casing comprising upper and lower sections adapted to be assembled to embrace the said eccentric and disposed in spaced relation to the periphery thereof, the said

casing having inner annular ball races alined with the ball races in the said disk, a 25 plurality of ball bearings mounted in the ball races and contacting with the disk and the said casing, a clamp band secured to the said casing and including two co-acting curved portions terminating above the center of the said casing and means for bolting the said portions together, the said portions having their terminals fixed to the lower portions of the casing, ears provided at the opposite ends of the semi-circular portion 30 and a bolt included in the said means and extended through the said ears to draw the said semi-circular portions together for holding the said casing in assembled position.

In testimony whereof I affix my signature in presence of two witnesses.

ANTON N. BIRKLAND.

Witnesses:

A. HEGNESS,
ALBERT BIRKLAND.
